UNITED STATES PATENT OFFICE

2,328,369

THEATER SOUND SYSTEM

Albert Le Roy Upton, St. Louis, Mo.

Application July 31, 1942, Serial No. 453,125

2 Claims. (Cl. 179—1)

This invention relates to theater sound systems.

The conventional sound system in a motion picture theater includes apparatus in a projection booth where a recording incident to a motion picture is run to initiate signals. These signals are amplified in equipment usually in the booth, from which an electric circuit runs to a loud speaker, or horns, on a stage at the rear of a screen. The present invention has as its object the provision of convenient and satisfactory means whereby the loud speaker may be used to serve as a reproducer for other than such recordings. The pickup for the second source may be a microphone, phonograph, or radio receiver. A further object of the invention is to provide remote control means whereby the input from either of the two sources may be connected and disconnected at a single place. Another object is to provide a means whereby the source of the input in a system of the character described may be changed with avoidance of voltage surges and noise.

These objects, and the construction and operation of the system will be apparent from the following detailed description, taken in connection with the accompanying drawing.

The drawing is a circuit diagram of a system embodying the invention.

Lines 1 and 2 carry audio frequency signals and lead from an amplifier, usually placed in the projection booth. In a conventional system continuances of these lines, identified as 3 and 4 respectively and 5 and 6 respectively, lead to a loud speaker 7, or speakers, on the stage at the rear of a projection screen. The line sections 3 and 4, shown in dotted lines, may be eliminated in the present system. They are shown so it may be understood how the present invention is used to modify the conventional system.

Leads 9 and 10 are connected to lines 1 and 2 respectively, and lead to switches 11 and 12. The switch 11 may connect the lines 1 and 2 through their leads 9 and 10 with lines 13 and 14 to a control panel. The switch 12 may connect the lines 1 and 2 through the leads 9 and 10 to leads 15 and 16, which are connected to the lines 5 and 6 respectively, thus providing a direct path comparable to the line sections 3 and 4.

It will be understood by closing the switch 11 on the terminals for the lines 9 and 10, that the circuit 1, 2 from the projection booth is connected to the control panel, and here as later described, connections may be made with the circuit 5, 6 leading to the loud speaker on the

stage. If, however, this remote control is not desired, the switch 11 is opened and the switch 12 is closed on the terminals for the lines 9 and 10, thereby connecting the lines 1 and 2 directly with the lines 5 and 6 (through leads 15 and 16) in much the same direct fashion as if the lines 1 and 2 were connected with the lines 5 and 6 through the original path 3 and 4.

The switch 12 is a double throw switch so that it may be closed not only on the terminals for the lines 9 and 10, but also on the terminals for the leads 17 and 18 which lead from the control panel, whereby the circuit selected at the control panel is connected to the stage speaker 7.

A double throw switch 19 on the control panel has its blades connected with the leads 17 and 18 (and when the switch 12 is properly set, are connected to the speaker 7) and is adapted to connect these leads with the lines 13 and 14, or with the lines 21 and 22. The latter pair of lines are connected in a manner hereinafter described, with a bridging amplifier 23 receiving its input signal from a source other than the projection booth, such as a phonograph, microphone, or radio receiver. The system illustrated and described in my copending application filed on even date herewith may be used as such source.

A ballast resistor 24 may be placed across the lines 13 and 14 by one blade of a switch 25. For convenience the switch 25 has a double blade, one blade connecting the resistor 24 as described, while the other blade connects an A. C. supply circuit 26 with an indicating lamp 27.

The line 21 branches; one branch being connected with a switch 29, the other branch being connected to a ballast resistor 30. The resistor 30 is connected by a line 31 to the output of the amplifier 23. The switch 29 is arranged to connect with a branch 32 of the line 31, to by-pass the resistor 30, or with a branch 33 of the line 22, which is connected to the output of the amplifier opposite the line 31.

When the switch 29 is connected to the branch 32 and the switch 19 is closed on the lines 21 and 22, a direct path is provided for the projecting amplifier to the stage speaker 7, assuming of course that the switches 11 and 12 are connected for remote control.

It has already been described how the lines 1 and 2 may be connected directly to the stage horns by the switch 12, but when that switch is closed on the terminals of the lines 17 and 18, and the switch 11 is closed, the system is connected for operation by remote control through the switch 19 on the control panel. If remote

control is not desired, the switch 11 is open and the switch 12 is closed on the lines 9 and 10. If, however, it is desired to operate the system at the remote control panel (which includes the switches 19, 25 and 29) the switch 11 will be closed and the switch 12 will be closed on the terminals for the lines 17 and 18.

Then if it is desired to connect the speaker 7 (that is through the lines 5 and 6) with the amplifier 23, the switches on the control panels will be operated in the following sequence: The switch 25 will be closed, the switch 19 will be closed on the terminals for the lines 21 and 22, and the switch 29 will be closed on the terminals for the branch 32. Thereupon the path from the amplifier 23 will be through the line 34, the branch 32, switch 29, line 21, switch 19, lead 17, switch 12, line 15, to line 5; while the path from the opposite side of the amplifier will be through line 22, switch 19, line 18, switch 12, line 16, to line 6.

When it is desired to change the connection on the control panel from the amplifier 23 to the lines 1 and 2, the switches on the control panel are changed in the reverse order. The switch 29 is connected with the branch 33; then the switch 19 is reversed to connect the leads 13 and 14; and the switch 25 is opened. Thereby the lines 1 and 2 are connected to the leads 9 and 10; switch 11, leads 13 and 14, switch 19, leads 17 and 18, switch 12, leads 15 and 16, to lines 5 and 6.

A constant impedance attenuator 34 may be used to control the input to the amplifier 23.

It will be understood that the switches 11 and 12 are intended to be operated only when the amplifier connected through them is dead. In operation, however, when the switches 25, 19 and 29 are operated in the order specified, the resist-

ors 24 and 30 completely protect the amplifiers, and the switches may be operated both without danger of damage to the amplifiers, and without any noise in the speaker.

It will be obvious that various changes may be made in the details of construction, within the scope of the appended claims, without departing from the spirit of this invention. Parts of the invention may be used without the whole, and improvements and additions may be made thereto while retaining the essence of the invention.

I claim:

1. In a sound system a pair of circuits each fed by an audio amplifier, a loud speaker and a circuit thereto, a double throw switch adapted to connect either amplifier circuit with the speaker circuit, a ballast resistor, and a selector switch for selectively connecting said resistor in one of the amplifier circuits and to by-pass said resistor, a line being connected to the selector switch and arranged to by-pass said double throw switch when the resistor is connected in said amplifier circuit by the selector switch.

2. In a sound system a pair of circuits each fed by an audio amplifier, a loud speaker and a circuit thereto, a double throw switch adapted to connect either amplifier circuit with the speaker circuit, a ballast resistor, a switch for connecting and disconnecting said resistor across one amplifier circuit, a second ballast resistor, and a selector switch for selectively connecting said second resistor in the other of the amplifier circuits and to by-pass said second resistor, a line being connected to the selector switch and arranged to by-pass said double throw switch when the second resistor is connected in said amplifier circuit by the selector switch.

ALBERT LE ROY UPTON.
